(57) **CLAIM**

The ornamental design for a wireless communications gateway, as shown and described.

DESCRIPTION

FIG. 1 is a perspective view of a wireless communications gateway showing my new design;

FIG. 2 is top plan view of the wireless communications gateway of FIG. 1;

FIG. 3 is left-side of the wireless communications gateway of FIG. 1;

FIG. 4 is a rear view of the wireless communications gateway of FIG. 1;

FIG. 5 is right-side of the wireless communications gateway of FIG. 1;

FIG. 6 is a front view of the wireless communications gateway of FIG. 1; and,

FIG. 7 is bottom plan view of the wireless communications gateway of FIG. 1.

The broken lines encompassing unshaded regions represent the bounds of the claimed design while all other broken lines are directed to environment and are for illustrative purposes only; the broken lines form no part of the claimed design. The crisscross pattern schematically depicted in FIGS. 1, 2, 3, 4, 5 and 7 indicates a change in material that is continuous throughout the surface on which the pattern is shown.
